US00D767737S

(12) **United States Design Patent** (10) Patent No.: **US D767,737 S**
(45) Date of Patent: **** Sep. 27, 2016**

(54) **GAS LIFT PLUNGER WITH CURVED,
UNDERCUT GROOVES**

(71) Applicant: **EPIC LIFT SYSTEMS LLC**, Fort Worth, TX (US)

(72) Inventor: **Schuyler Kuykendall**, Granbury, TX (US)

(73) Assignee: **Epic Lift Systems LLC**, Fort Worth, TX (US)

(**) Term: **14 Years**

(21) Appl. No.: **29/518,859**

(22) Filed: **Feb. 27, 2015**

(51) LOC (10) Cl. **23-01**

(52) U.S. Cl.

USPC **D23/266**

(58) **Field of Classification Search**

(57) **CLAIM**

The ornamental design for a gas lift plunger with curved, undercut grooves, as shown.

DESCRIPTION

FIG. 1 is a perspective view of a gas lift plunger with curved, undercut grooves between radial extensions.

FIG. 2 is another perspective view of the gas lift plunger with the curved, undercut grooves between the radial extensions.

FIG. 3 is side view of the gas lift plunger with the curved undercut grooves between the radial extensions.

FIG. 4 is a side, cross-sectional view taken along the line 4-4 of FIG. 2, illustrating the externally-visible curved, undercut grooves between the radial extensions; and,

FIG. 5 is an enlarged, side, cross-sectional view, as indicated in FIG. 4, of the gas lift plunger, showing the externally-visible curved, undercut grooves between the radial extensions.

The broken lines depict portions of the article that form no part of the claimed design.

1 Claim, 2 Drawing Sheets
